P. H. JACKSON,
Boat Detaching.

No 64,110.

Patented Apr. 23, 1867.

Peter H. Jackson

United States Patent Office.

PETER H. JACKSON, OF NEW YORK, N. Y.

Letters Patent No. 64,110, dated April 23, 1867.

IMPROVED BOAT-DETACHING TACKLE.

The Schedule referred to in these Letters Patent and making part of the same.

TO ALL WHOM IT MAY CONCERN:

Be it known that I, PETER H. JACKSON, of the city and State of New York, have invented, made, and applied to use a certain new and useful improvement in Disengaging-Apparatus for Boats; and I do hereby declare the following to be a full, clear, and exact description of the said invention, reference being had to the annexed drawing, making part of this specification, wherein—

Figure 1 is a plan of a boat fitted with my improvement; and

Figure 2 is a longitudinal section of the said boat and mechanism.

Similar marks of reference denote the same parts.

Various devices have heretofore been made for disconnecting the boats at both ends simultaneously from the chains or ropes leading to the davits. These, however, have in many instances been complicated and unreliable.

The nature of my said invention consists in a pair of horizontal bolts, running below the thwarts and taking eyes upon the davit-falls that are placed within mortises into which said bolts pass, and when the boat is to be disconnected it is to be effected by withdrawing these bolts by a lever and screw acting equally on both bolts, so that the disconnection shall be simultaneous.

In the drawing, *a* represents the boat, *b b* the thwarts; *c c* are the mortises for receiving the links or rings *d d* of the davit-fall, or of the ropes or chains passing to the davits. These mortises *c c* are made in suitable metallic plates or sockets, attached to the boat in any desired manner. The bolts *e e* pass through the sides of the metallic plates forming the mortises *c*, and extend under thwarts *b*, and are supported in guides *f*. *g* is a cylinder, having a feather, *i*, around its periphery, near the centre, taking a fork, *h*, that is attached to the bottom of the boat. In this cylinder *g* screw-threads are cut, taking right and left-handed screws formed at the end of the bolts *e e*, and *k* is a lever by which the cylinder *g* is rotated to withdraw or project the bolts *e e*. This is effected with uniformity at the two ends of the boat, as the feather *i* prevents any end movement of the said cylinder *g*, and the right and left-handed screws are of the same pitch. At the ends of the bolts screws *l l* may be inserted on the opposite sides of the mortises *c c*, so as to adjust with accuracy the point to which the bolts may be moved endwise and insure uniformity of disconnection.

What I claim, and desire to secure by Letters Patent, is—

The cylinder *g*, feather *i*, lever *k*, and fork *h*, in combination with the bolts *e e*, having right and left-handed threads, said bolts taking eyes or rings on the ropes or chains passing to the davits, as set forth and for the purposes specified.

Dated February 19, 1867.
